[57] CLAIM

The ornamental design for an article holding device, as shown and described.

DESCRIPTION

FIG. 1 is a top plan view of an article holding device showing my new design;

FIG. 2 is a front elevation view shown broken away to indicate indeterminate length thereof;

FIG. 3 is a bottom plan view thereof;

FIG. 4 is a fragmentary, side elevation view thereof; and, FIG. 5 is a front, side elevation view of an article holding device shown broken away to indicate indeterminate length on a reduced scale in condition of use on a fireman's jacket. The fragmentary criss-cross pattern shown in the drawing is understood to represent woven cord and is repeated uniformly throughout the areas shown.

The broken line showing of a slidable clamping mechanism and a fireman's jacket are for illustrative purposes only and form no part of the claimed design.
